[57] **CLAIM**

The ornamental design for a sink, substantially as shown and described.

DESCRIPTION

FIG. 1 is a perspective view taken from the front, top and left side of a sink showing my new design;

FIG. 2 is a top plan view thereof;

FIG. 3 is a bottom plan view thereof;

FIG. 4 is a front elevational view thereof;

FIG. 5 is a right side elevational view thereof; and

FIG. 6 is a rear elevational view thereof, with the actuating levers omitted for convenience of illustration.

*Fig. 1.**Fig. 2.**Fig. 3.*Fig. 6.

Fig. 5.

Fig. 4.
